Specification of Letters Patent

Patented Sept. 9, 1913.

Application filed October 24, 1905, Serial No. 264,222. Renewed December 14, 1907. Serial No. 406,494.

To all whom it may concern:

Be it known that I, MATTHEW VIERENGEL, a citizen of the United States, residing at New York, in the borough of Brooklyn, county of Kings, and State of New York, have invented a new and useful Printing-Press, of which the following is a specification.

This invention relates to that type of printing presses in which the printing is done by means of a flat type or form-bed and an oscillating impression cylinder. In these presses the bed is reciprocated on fixed guides, and the impression cylinder rotates 15 on its axis in one direction while the bed is moved to make an impression, and in the opposite direction when the bed makes its backward movement after the impression is completed.

My improvements relate to a special construction of this type of printing presses in which the cylinder is arranged to reciprocate simultaneously with the bed and in the opposite direction so that the travel of 20 the bed forward and back is reduced one-half, the other half of the distance required for making the impression being traveled by the cylinder, whereby the time required for making an impression and the return of 25 the cylinder and bed is reduced one-half, which makes it possible to print, by this press, with double the rapidity of an ordinary flat-bed oscillating cylinder press running at the same speed.

The object of these improvements is, first, to provide the oscillating cylinders of these printing presses with means for moving the same vertically and thus adapt the said cylinder to co-act with the bed in making an 30 impression by being moved downward, positively, in contact with the form on the bed and locked in that position, and to carry the sheet and impress it upon the type or form as said cylinder rotates on its axis and moves 35 backward, while the bed moves forward, and to move up off the form at the end of an impression, and remain out of contact therewith during its rotary and forward movement to take another sheet and while the bed 40 is moving backward after an impression has been completed.

A further object of this invention is to intercept the descent of the impression cylinder when the feeding of the sheets is interrupted from any cause, and thereby prevent

contact of the blanket with the inked-form; and this object is obtained automatically by the action of a device which, when there is no sheet on the feed-board, is caused to uncouple the mechanism by which the cylinder 60 is pulled down in contact with the form, the cylinder being thereby prevented from descending during every forward or printing movement until the feeding is resumed.

A further object of the invention is to reduce the strain on the bed and cylinder driving mechanism while passing the dead-centers; and this object is brought about by means whereby the depressing and raising of the impression cylinder at the beginning 70 of its forward or printing movement and also on its return or backward movement, is slow, gradual and easy, relative to the speed of the bed and cylinder driving mechanism.

A further object of the invention is to provide this type of press with mechanism for moving the bed that will insure a smooth, even and practically noiseless movement thereof, both forward and back, and when passing the centers; and this object is secured by coupling the bed to rock-levers operated by a pitman connected to a wrist-pin supported between a crank-wheel and an arm on a shaft so that the power is applied on the longitudinal middle line of the press, 85 and the bed is moved from both sides by the rock-levers, and is thus prevented from twisting and getting out of true or vibrating laterally, during its movements.

Finally, this invention has for its object 90 to construct a relatively short and compact reciprocating-bed printing press capable of running at a high speed and with a movement of the bed of about one-half the length of the form and to provide such a press 95 with a driving mechanism for the reciprocating bed, and incidentally for the cylinder, which shall be located mainly beneath the bed and adapted to operate in a space but little greater in length than the space 100 in which the bed moves in making an impression.

The invention consists in the novel parts, improvements, and combinations herein disclosed.

The accompanying drawings, which are referred to herein and form a part hereof, illustrate one embodiment of the invention and serve in connection with the description to explain the principles of the invention.

Of the drawings: Figure 1 represents a side-elevation of the right-hand side of my improved printing-press. Fig. 1^a represents the cams for lifting and depressing the impression cylinder. Fig. 2 is a front-end elevation of the printing-press. Fig. 3 is an elevation of the left-hand side of the same. Fig. 4 is a perspective view of the form-bed, impression cylinder and the racks by which the cylinder is operated and reciprocated. Fig. 5 is a diagrammatic view of the impression cylinder and the form-bed, illustrating their movements. Fig. 6 is a longitudinal vertical section of the printing press taken on line *z-z* of Fig. 2. Fig. 7 is a detached end view of the feed-board and the arm by which the throw-off mechanism is controlled. Fig. 8 is a detailed plan of the plate on the feed-board showing the grid which permits the arm to drop down and thus operate the throw-off mechanism. Fig. 9 is an edge view of the feed-board and the arm showing the position of the arm when a sheet is on the feed-board, and its position when there is no sheet on the feed-board.

Referring to the drawings the frame of the press comprises a base —A—, side members —B—B'— which are composed of bottom plates —C—, uprights —D—D'—D²— and top plates —E—; these parts of each side member being cast as integral parts of each other. The side members —B—B'— are connected together transversely at the center by a brace —F— bolted to the central uprights —D—D'— of the side members. This brace has a rectangular opening —G— therein through which the pitman and connecting rods, hereinafter referred to, operate. The side members are bolted to the base —A— and to the transverse brace —F— securely, to form a strong, firm, non-vibrating support for the moving members of the press. On the inside of the top plates —E—E²—, and just above the bottom edges thereof, there are guideways —1—1— and brackets —2—2— cast thereon.

—H— is the type or form bed which is constructed in the usual manner and has at the front and rear ends shafts —3—4— which are journaled in bearings in the side and center ribs of the bed, and have on their ends, which project through the bearings, rollers —5—6— respectively. These rollers rest on the guideways —1—1—. The bed is further supported by central rollers —7—7—8—8— (only one of the latter being shown) which are mounted on short shafts in the forked upper ends of the adjustable plates —9—10—. On these rollers the flanged bases of the longitudinal ribs —11—12— of the bed rest and move when the bed is reciprocated.

The adjustable plates —9—10— are connected with the brace —F— by bolts passed through slot in the plates and screwed into

the said brace so that these plates are susceptible of vertical adjustment. The bases of the adjustable plates are connected with the upper ends by set-screws —13—14—, socketed in the brackets —15—16— connected with the brace. By means of these set-screws the central rollers —7—7—8—8— can be adjusted to the bottoms of the ribs —11—12— and thus furnish a firm, and substantially frictionless, support for the bed at the center.

Bed movement.—The bed is pivotally connected at the rear with upright levers —17—18— by coupling the shaft —4— to the levers which are constructed to serve as pivotal bearings for the said shaft. These levers are connected together transversely by a bar —49—. A pitman —20— connects this bar with a wrist-pin —21— on a crank-wheel —22— mounted on a shaft —23— journaled at the front of the machine in the bearings of a pillow-block —24— and a lateral projection of the upright —D— of the right-hand side member of the frame. The wrist-pin is lengthened so as to project through the pitman connection and into and through a bearing —25— in the end of an arm —26— on a shaft —27— journaled in bearings in the pillow-block —24^a— and a lateral projection of the upright —D— on the left-hand side of the machine. This construction furnishes support for the wrist-pin at both ends, thereby giving a firm and steady connection of the pitman with the crank-wheel which conduces to the easy and comparatively noiseless movement of the bed. The lower ends of the levers —17—18— are fulcrumed on a transverse bar —28—, and this bar is coupled to an adjustable vibrating link —29— mounted on a bar —30— supported in the lower parts of the pillow-blocks —24—24^a.

The crank-wheel —22— meshes with a driving pinion —31— which is mounted on the driving shaft —8— which is journaled in bearings in lateral projections of the central uprights —D'—D'— of the side frames. The driving shaft carries on one end fast and loose pulleys —32—33—. The crank-wheel —22— is rotated by the driving pinion —31— and through the pitman —20— vibrates or oscillates the levers —17—18—, and this, in turn, reciprocates the type or form bed —H—.

The sides of the bed have connected with them horizontal rack-bars —34—34— and these rack-bars are provided with longitudinal flanges —35—35— that project under similar but opposing flanges —36—36— on plates —37—37— bolted to the side members of the frame. The bed is thus held against vertical displacement, between the guideways —1—1— and the flanges —36—36— of plates —37—37—.

The cylinder movement.—The impression

cylinder $-I-$ is mounted on a shaft $-38-$ the ends of which are journaled in bearings in the cross-heads $-39-39-$ which are held in the guides formed by the upper and lower members $-40-41-$ of the vertically adjustable side-frames $-J-J-$. The ends of the cylinder shaft $-38-$ project through the bearings in the cross-heads and carry pinions $-42-42-$ which are in gear with rack-bars $-43-43-$ bolted to the lower members $-41-41-$ of the frames $-J-J-$. The members $-40-41-$ are connected together at their ends by means of rods $-44-44-$ passed down through perforations in said members. The members $-40-40-$ are clamped on the upper ends of the rods between nuts $-45-46-$, and the members $-40-40-$ are held up in their proper position relative to members $-41-41-$ by the collars $-47-48-$ on the rods that rest on the bottom members $-41-$. The frames $-J-J-$ are connected with the top-plates $-E-E-$ of the press frame by the rods $-44-44-$ which are passed down through holes $-49-50-$ in the top plates and project through the bottom thereof. The bottom members $-41-41-$ are also provided with sockets $-51-$ in their undersides. Spiral springs $-52-$ in the sockets bear against the bottom of the sockets and press the frame $-J-J-$ upward, and thereby tends to lift the impression cylinder off the form bed.

K-K- are cams which are located underneath each of the top plates $-E-E-$ in line with the rods $-44-44-$ and the ends of the frame $-J-J-$. These rods pass through the cams. The cams comprise a fixed member $-53-$ fastened by screws to the top plate $-E-$ and a rotatable member $-54-$ which is held on the rod by means of the holding nuts $-55-$ screwed on the ends of the rods. The opposing faces of the members of the cams are provided with radial ribs $-56-57-$ respectively, and the edges $-58-$ of the ribs of the fixed member of the cam, and the opposite edges $-59-$ of the ribs of the rotatable member $-54-$, are inclined in opposite directions so that when the lower member is rotated in one direction the inclined edges of its ribs pass up the inclined edges of the ribs of the fixed member and thus separate the two members, and as the rotatable member bears against the holding nuts on the end of the rod, it draws the rod downward.

From the above it will be seen that if all the members $-54-$ of the cams are rotated simultaneously, the rods $-41-$ are caused to pull the frames $-J-J-$ downward against the resistance of the spiral springs $-52-$ and thereby the impression cylinder is depressed and brought in contact with the form on the bed.

The rotation of the movable members of

the cams is produced by the following mechanism: The rotatable members are provided with arms $-60-$ and the members on the same side are coupled together by means of a bar $-61-$ the rear end of which is provided with a slot $-62-$ to receive the tenon $-63-$ on the upper ends of the rockers $-64-$ which are keyed to a transverse rod $-65-$ mounted in the upward projections $-66-66-$ of the pillow-blocks $-24-24-$. The rockers $-64-64-$ are vibrated by means of a grooved cam $-67-$ mounted on the shaft $-33-$, which actuates an arm $-68-$ keyed to a rock-shaft $-69-$ supported in bearings in the pillow-blocks $-24-24-$ and having a roller on its upper end that runs in the groove of the cam. The upper end of the arm $-68-$ is pivoted to the end of a reach-rod $-71-$ the opposite end of which has a notch $-70-$, that engages a stud $-72-$ on the rocker $-64-$ on the right-hand side of the machine. The operation of this mechanism is as follows: When the press is running and the bed completes its backward movement after an impression has been made and just before or at the beginning of its forward movement, the roller on the arm $-68-$ enters the low part of the cam-groove and the arm $-68-$ is pulled forward, and by means of the reach-rods $-71-$ draws the rockers back and thereby the coupling bars $-61-$ are moved forward and caused to turn the rotatable members of the cams to the right, whereupon the ribs slide up the incline to the tops of the ribs of the fixed members and thereby draw the frames $-J-J-$ down and the cylinder is depressed against the form. When the bed arrives near the end of its forward movement and the cylinder at the end of its rear or back position, the roller enters the high part of the groove in the cam and the rotation of the arm, reach-rod and rockers, is reversed and thereby the movable members of the cams are rotated to the left and its ribs pass down the inclines to a position where the ribs of the two members interlock, thus releasing the rods, whereupon the compressed spiral springs $-52-$ react and lift the frames $-J-J-$, and the cylinder is raised so that it clears the form while moving forward and during the backward movement of the bed.

The cylinder in addition to its vertical movement has an oscillating motion on its axis and a reciprocating motion parallel, but in an opposite direction, to that of the bed. The oscillating motion is produced by the bed rack-bars $-31-31-$ which are in gear with the toothed-wheels $-73-73-$ mounted on the cylinder-shaft at the ends of the cylinder. When the bed moves forward to make an impression the cylinder is rotated by the rack-bars to the right and,

on its backward motion, the cylinder is rotated to the left.

The reciprocating motion of the cylinder is produced by the pinions 42-42 engaging the stationary rack-bars 43-43.

When the bed moves forward and the cylinder turns on its axis, the pinions 42-42 being in mesh with the teeth of the rack-bars 43-43, the cylinder and the cross-heads 39-39 are forced to move backward. The bed and the cylinder are thus moved away from a fixed point at the same time, in opposite directions at the same speed, whereby the distance traveled by the bed during both its printing and return movement is reduced one-half, the remainder of the movement necessary for making an impression being accomplished by the backward movement of the cylinder.

20 By reason of the fact that the cylinder is mounted in independent cross heads 39-39 arranged to reciprocate in the frames J-J at the opposite sides of the machine, the said frames may be made of a minimum length and thereby given the maximum strength and stiffness for a given weight of metal, it being observed that the upper members 40 of the frames J-J are required to take the entire strain of the impression. As the slightest spring of these members 40 would give rise to an unevenness in the impressions it is important that said members should be made extremely rigid. This is rendered possible without unduly increasing their size by keeping their length as short as possible for a given length of travel of the impression cylinder. Another important feature of the construction resides in the arrangement of the fixed racks 43 outside of the frames J-J so that the bearings for the impression cylinder may be arranged as close as possible to the ends thereof. By reason of this construction undue spring of the shaft of the impression cylinder under the force of the impressions is avoided. Another important feature of this construction consists in the arrangement of the fixed racks 43 upon the frames J-J so that said racks although 50 fixed against longitudinal movement rise and fall with the frames and thereby remain in full mesh with the pinions 42 on the ends of the cylinder shaft. All lost motion between these racks and pinions is thereby avoided. If the racks were fixed on the frame the pinions would be moved partly out of mesh therewith when the cylinder is raised on the return stroke and this lost motion would be added to the lost motion between the gears 73 and the racks 34 and would be far more objectionable than the latter lost motion because of the smaller size of the pinions 42 as compared with the gears 73.

60 *Inking apparatus.*—The form-rollers

74 and the distributing-rollers consisting of vibrating rollers 75-75 and a composition roller 76 are mounted in a carriage L consisting of side-members which are fastened to slides 77-77 that rest on the top of the flanges 36-36. The carriage L is connected with the cross-heads 39-39 by means of links 77a-77a. The carriage travels backward and forward in front of and with the cylinder. The ink-fountain 78 is fastened to the rear end of the frame just below the top. The fountain-roller 79 is fitted with a ratchet-wheel 80 on the end of its shaft and on the end of the same shaft outside of the fountain, an arm 81 carrying a pawl 82 is mounted and has a pin 83, on the end opposite the pawl, which is engaged by a pitman 84 pivoted to a crank-pin 85 on a slide 86 held in guides 87 on the outside of a cam 88. By the revolution of the said cam a reciprocating motion is given to the pitman 84, and the pitman, in turn, swings the arm 81 and causes the pawl 82 to engage the teeth of the ratchet-wheel 80 and thus rotate, intermittently, the fountain-roller. The extent of the movement of the fountain-roller by the swing of the arm is, of course, governed by the distance of the crank-pin 85 from the center of the cam 88. In the extended side walls of the fountain near the bottom, and between the fountain roller and the frame of the press, a shaft 89 is journaled in suitable bearings. This shaft carries two upright arms 90-90 in the upper ends of which are bearings for the gudgeons of a supply-roller 91. The shaft 89 also carries at one end a pendulum arm 92 fitted with a roller 93 that bears against the face of the cam 88 on the right-hand side of the press, which is mounted on a shaft 94 journaled in bearings in the rear uprights D² of the side frames B-B'. The shaft 94 also carries on the same side and behind the cam a spur-wheel 95 which is in gear with an idle-wheel 96 on a stub-shaft 97 that carries also a sprocket-wheel 98 connected by means of a sprocket-chain 99 with a sprocket-wheel 100 on the driving shaft S. The idle-wheel is in gear with a pinion 101 on the end of a transverse shaft 102 mounted in bearings in the uprights just below the top of the frame. This shaft carries between the side frames a transfer-roll 103. The supply-roll 91 carries the ink from the fountain-roller to the transfer-roll, when it is swung over by means of the cam 88. To the top plates E-E on both sides and just over the uprights D², brackets 104 are bolted which project rearward of 130

the frame of the press. The ends of these arms are formed into bearings for a shaft —105— on which are mounted, loosely, arms —106—106—, and the ends of these arms are formed into bearings for the shaft —107— of a vertically oscillating ductor —108—. To the end of the shaft —107— on the left-hand side of the press, the upper end of a fork —109— is pivoted, the lower end being coupled to the shaft —94— and having a roller —110— on a stud thereon that bears against the face of a cam —111— mounted on the shaft —94—. When the press is running and the low part of the cam bears against the roller —110— the ductor —108— drops, by gravity, to the transfer-roll —103—, but when the high part of the cam bears against the roller the fork lifts the ductor to a horizontal position, as shown by Figs. 1, 3 and 6.

The form or type bed —H— has at its rear end an inking table —112— which, when the bed moves backward, is carried under the ductor —108—. The timing of the cam —111— is such that when the bed moves forward to make an impression the high part of the cam is in contact with the roller —110— and the fork is thereby caused to hold the ductor in such a position that it bears on the surface of the inking table as the latter moves forward and, when the inking table moves past the ductor, the roller reaches the low part of the cam and the fork drops and allows the ductor to swing down to the transfer-roll —103— and take the ink therefrom, and it remains in that position in contact with the transfer-roll until the inking table approaches on the return or backward movement of the bed, when the high part of the cam comes in contact with the roller and the cam lifts the fork and the ductor is thereby raised to its upper position where it bears on the surface of the inking table as it moves backward and transfers the ink it has taken from the transfer-roll to the surface of the inking-table. As the bed moves forward to make an impression and the cylinder moves backward the form-rolls —74— pass from the form to the inking-table from which they take a fresh supply of ink and, on the reverse movement, they also roll over the inking table and from that to the form. Thus, during both movements of the bed and cylinder, the form-rolls apply ink to the form and also take a fresh supply from the inking table. This inking mechanism is not claimed herein but forms the subject-matter of a co-pending application, Ser. No. 406,485, renewed December 14, 1907.

Automatic throw-off.—To the top of the frames —J—J—, brackets —113— are fitted, and these are formed with bearings in which is journaled the rocker-shaft

—114—. On the right-hand end of this shaft there is an arm —115— having a pin at the outer end on which is hung the upper end of a rod —116— that connects at its lower end with one arm of a bell-crank lever —116^a—, the other arm of said lever being connected by means of a horizontal rod —116^b— with a prop —117— pivoted at its lower end to an ear on the right-hand upright —D²—. This prop has a shoulder —117^a— near the upper end. To the inner-side of the upright —D²— a bell-crank lever —118— is fulcrumed on a stud-shaft. The lower arm of this bell-crank lever is provided with a roller which is in contact with the underedge of the reach-rod —7^a— and this arm is also provided with a pin —118^a— in line with the prop —117—, and in such a position that when the arm is lifted by the turning of the lever, the pin will be above the shoulder of the prop, which will pass under the pin when swung in line with it. The other arm of the bell-crank lever —118— projects up behind the shaft —94—, and it is also fitted with a roller which bears against a cam —119— on the shaft —94—. On the opposite side of the press the rocker-shaft —114— is provided with an arm —119^a— that is pivotally connected with the upper end of an inclined bar —119^b—, the lower end of which is slotted and coupled to the shaft —94—, and has a roller that bears against the face of a cam —120— on the same shaft. On the rocker-shaft —114—, about midway between the bearings and coincident with the middle line of the press, a collar —121— secured by a setscrew, connects with a suspension plate —121^a— the end of which projects a greater or less distance beyond the center of gravity of the shaft —114—, the overhang tending to gravitate and turn the shaft —114— to the left as shown in Fig. 6. An arm —122— has one end fastened rigidly to the underside of this plate, and its opposite free end convexly curved and slotted to form a grid —122^a—. This end is extended over the lower part of the feed-board —123— and is held directly over a plate —123^a— let into a recess in the feed-board, and which is slotted to form a grid —123^b— directly under the grid in the end of the arm, but the slots in one of the grids alternate with the bars in the other so that when the grid on the arm is turned down on the grid in the plate, by the gravitation of the suspension plate —121^a—, the convex bars of the former pass through the slots of the latter, and thus the curved part of the end of the arm is permitted to drop down below the surface of the grid on the feed-board, and thereby the shaft —114— is turned to the left and through its connections swings the prop over and carries its shoulder under the pin —118^a—. When there is a sheet on the

feed-board in position to be taken by the cylinder grippers it lies on the plate and the sheet being interposed between the grids, the arm is held up by the sheet and while 5 in this position the rocker-shaft and the arms thereon through the rod —116—, bell crank lever and rod —116^b— holds the prop back, and its shoulder out of line, vertically, with the pin —118^a—; but if the feeding is 10 intermittent accidentally or purposely, the grid end of the arm drops down through the grid in the plate by gravity and the prop is swung over so that its shoulder will arrest the downward movement of the arm of the bell-crank lever —118— and thereby the 15 reach-rod will be held up with its notch disengaged from the pin —72—, the cylinder depressing mechanism thrown out of gear and the cylinder retained in its upper 20 position out of contact with the form during its forward movement.

The prop is swung back to withdraw the shoulder from under the pin —118^a— when the cylinder begins its return movement toward the feed-board, so that the arm of the bell-crank lever can drop, and thus lower the reach-rod, so that its notch reengages the stud on the rocker, and thus couples up the cylinder depressing mechanism in time 25 to pull the cylinder down on its next rearward or printing movement, if the feeding has been resumed. To accomplish this the arm 119^a is positively connected with the upper end of the inclined bar 119^b by a 30 pin 124 on its end which is entered into a slot 124^a in the said bar so that when the bar is drawn down by the cam 120, the shaft 114 will be positively rocked in such direction as to swing back the prop 117 35 from its active position with relation to the lever 118. When the parts are in this position, the arm 122 will be elevated to the position shown in Figs. 1 and 3 and in full lines in Fig. 9. When there is a sheet on 40 the feed board and the bar 119^b is released by the cam 120, the downward movement of the grid 122^a at the end of the arm 122 is limited by contact with the sheet, this being the intermediate position indicated by the 45 dotted lines in Fig. 9. When the movement of the arm is thus limited by the sheet, the spring 124^b that holds the roller on the inclined bar 119^b against the face of the cam 120 lifts the bar without applying any pressure to the arm 122 by reason of the slot 124^a in the bar which moves idly on the pin 124. The arm 122 is thus permitted to rest against the paper lightly so as not to cause it to cut the paper between the slots. 50 When the arm 122 is thus arrested by the paper, the prop 117 is prevented from returning to its active position and the cylinder will be pulled down to printing position. If there is no sheet on the feed board 55 when the cam 120 releases the bar 119^b,

the grid on the end of the arm 122 drops through the slots of the grid in the feed board to the lower position indicated by dotted lines in Fig. 9, thereby turning the rock shaft 114 so as to move the prop 117 73 into active relation to the lever 118 and the cylinder will not be pulled down to the printing position. On the succeeding revolution of the shaft 94 the arm 119^b will be again drawn down, the arm 122 elevated to 75 the position shown in full lines in Figs. 1, 3, and 9, and the prop 117 removed to its inactive position the parts being then in position to receive the next sheet. The succeeding operation will depend upon 80 whether or not the sheet is supplied as above explained. To assist the weight of the arm 122 in moving the prop 117 and the intermediate connections and to regulate the pressure of the arm 122 on the sheet and thus adjust its pressure according to the strength of the paper, a pressure-regulating spring 125 is coiled on the shaft 114, one end being fastened to one of the brackets 113 and the other to a collar 126 90 adjustably secured to the shaft so that by increasing or diminishing the tension of the spring the force with which the grid end of the arm bears upon the paper can be regulated as desired. 95

The stationary rack-bars —43—43— which engage the pinions —42—42— and reciprocate the impression cylinder are fastened to the lower members of the frames —J—J— by means of bolts passed through 100 horizontal slots in the rack-bars so that they can be adjusted longitudinally. These rack-bars are also held against movement lengthwise by set-screws passed through pillars —127—127— and bearing against 105 the ends of the rack-bars.

My invention, considered in its broader aspects, is not limited to the particular construction herein shown and described nor to any particular construction by which the 110 same has been or may be carried into effect, as various changes may be made without departing from the main principles of the invention and without sacrificing its chief advantages. 115

I claim:

1. A printing press including a form-bed, a laterally reciprocating impression cylinder, a guide frame for the latter, springs to hold said frame in raised position, and cam-operated mechanism to lower said frame in opposition to said springs at predetermined times. 120

2. The combination, with the impression cylinder and the guide frame in which the same is laterally guided, of springs upon which said frame rests, and means acting on said frame at the corners thereof to pull the same in downward direction in opposition to said springs. 125 89

3. The combination, with the impression cylinder, of the guide frame therefor and comprising side frames having spaced upper and lower members, springs interposed between the lower members of said side frames and the frame of the press, rods passing through the members of said side frames, and means acting on said rods to pull the same downwardly at predetermined times. 5
4. The combination, with the impression cylinder and the guide frame in which the same is laterally guided, of springs upon which said frame rests, a plurality of rods secured to said frame and extending downwardly into the frame of the press, and means for simultaneously pulling all of said rods in downward direction during the printing movement. 10
5. The combination, with the impression cylinder and the guide frame in which the same is laterally guided, of springs upon which said frame rests, a plurality of rods secured to said frame and extending downwardly into the frame of the press, a cam to pull down each rod, and an operative connection between said cams. 15
6. The combination, with the impression cylinder and the guide frame in which the same is laterally guided, of springs upon which said frame rests, a plurality of rods secured to said frame and extending downwardly into the frame of the press, a cam for pulling down each rod, couplings between said cams whereby they are all simultaneously operated to depress and release said rods, and means for actuating said couplings. 20
7. The combination of the guide frame for the impression cylinder which comprises the opposing side members, means to normally maintain said frame in raised position, rods secured to said side members at the ends, cams to move said rods and each comprising a fixed and a rotatable member, and means whereby all of said rotatable members are simultaneously actuated. 25
8. In a printing press, the combination of a form-bed, a reciprocating impression cylinder movable over the same, means for intermittently raising and lowering said cylinder to effect the printing and return movements thereof, and means for automatically discontinuing such raising and lowering of the cylinder when the feeding of the sheets is interrupted. 30
9. In a printing press, the combination of a reciprocating form-bed, a reciprocating and oscillating impression cylinder, means for normally holding said cylinder out of contact with the form, means for intermittently depressing said cylinder to effect the printing movement, and means whereby said last-named means is automatically rendered inoperative when the feeding of the sheets is interrupted. 35
10. In a printing press, the combination of a form-bed, a reciprocating impression cylinder, a frame in which the latter is guided over the form, means acting on said frame to normally maintain said cylinder out of printing contact with the form, mechanism for depressing said frame intermittently, and automatically operated means for uncoupling said depressing mechanism when the feeding of the sheets is discontinued. 40
11. In a printing press, the combination of a form-bed, a reciprocating impression cylinder, a frame in which the latter is guided, a feed-board, and mechanism by which said frame is alternately raised and lowered to effect the printing movement only when the sheets are placed without interruption on said feed-board. 45
12. In a printing press, the combination, with the depressing mechanism for the impression cylinder, of a feed-board having a grid, a gravity-controlled arm having a grid to coöperate with said first-named grid, and coupling mechanism for said depressing mechanism controlled by said arm. 50
13. In a printing press, the combination of a form-bed, a reciprocating impression cylinder, a frame in which said cylinder is guided, means for holding said frame in raised position, means for intermittently lowering said frame, and means for automatically throwing said last-named means out of operation when the feeding of the sheets is intermittent. 55
14. In a printing press, the combination of a form-bed, a reciprocating impression cylinder, a frame in which said cylinder is guided, means for holding said frame in raised position, means for intermittently lowering said frame, a feed-board, and means automatically operated when said feed-board is uncoupled to throw said lowering means out of operation. 60
15. A printing press including in combination, a reciprocating form bed, a rack carried at each side thereof, a second rack arranged at each side of the bed and fixed against longitudinal movement, an impression cylinder, two gears at each end of the impression cylinder each meshing with one of said racks, a bearing for each end of the impression cylinder, each bearing being arranged between the gears at the corresponding end of the cylinder, and means acting through said bearings for raising and lowering the cylinder. 65
16. A printing press including in combination, a reciprocating form bed, a rack carried at each side thereof, a second rack arranged at each side of the bed and fixed against longitudinal movement, an impression cylinder, two gears arranged at each end of the impression cylinder each meshing with one of said racks, and a vertically reciprocating frame in which each end of 70

the impression cylinder is mounted, each of said frames being arranged between the racks and gears at the corresponding side of the machine.

17. A printing press including in combination, a reciprocating form bed, an oppositely reciprocating impression cylinder geared to said bed, a frame in which each end of said impression cylinder is mounted, and means mounted independently of said cylinder for moving said cylinder-carrying frames, each as a whole, in a direction transverse to the path of movement of the cylinder while retaining said path in substantially parallel relation to the form bed.

18. A printing press including in combination, a reciprocating form bed, an oppositely reciprocating impression cylinder geared to said bed, a vertically reciprocating frame in which each end of said impression cylinder is mounted, a rack fixed on each frame, and a pinion fixed at each end of the impression cylinder and arranged to mesh with the rack on the corresponding frame.

19. A printing press including in combination, a reciprocating form bed, an oppositely reciprocating impression cylinder geared to said form bed, a vertically reciprocating frame in which each end of said

impression cylinder is mounted, a rack fixed on each frame, and a pinion fixed at each end of the impression cylinder and arranged to mesh with the rack on the corresponding frame, said vertically reciprocating frames being arranged between the said last mentioned racks and pinions and corresponding ends of the impression cylinder.

20. A printing press including in combination, a reciprocating form bed, an oppositely reciprocating impression cylinder having journals at its opposite ends, a frame in which each end of said impression cylinder is mounted, independent bearings arranged between said frames and the journals at the corresponding ends of the cylinder, and means mounted independently of the cylinder for moving said frames each as a whole in a direction transverse to the path of movement of the cylinder while retaining said path in substantially parallel relation to the form bed.

In testimony that I claim the invention above set forth I have affixed my signature in presence of two witnesses.

MATTHEW VIERENGEL.
